OF BROOKLYN, NEW YORK.

VAPOR-LAMP.

1,099,193.

Specification of Letters Patent.

Patented June 9, 1914.

Application filed June 20, 1913. Serial No. 774,777.

To all whom it may concern:

Be it known that I, CHARLES NELSON, a citizen of the United States, and residing in the borough of Brooklyn, in the county 5 of Kings, city and State of New York, have invented a certain new and useful Vapor-Lamp, of which the following is a specification.

This invention relates to a vapor lamp 10 of the type illustrated in my co-pending application for patent filed January 17, 1913, Serial No. 742,547.

The object of the invention is to improve the devices for priming or introducing 15 liquid fuel into the priming pan preparatory to starting the lamp. This and further objects will more fully appear from the following specification and accompanying drawing, considered together or separately.

20 In the drawings, Figure 1 is a vertical section of a lamp embodying the invention. Fig. 2 is a section on the line 2—2 of Fig. 1; and Fig. 3 is a vertical section of the pump shown in Figs. 1 and 2, but on an 25 enlarged scale.

In all the views, like parts are designated by the same reference characters.

The font 1 is circular in plan. It is preferably made of sheet metal so as to 30 be both liquid and vapor tight. The liquid fuel is introduced through a feeding opening, which is normally closed by a suitable cap 2, which is shown as attached in place by means of screw-threads. In the center 35 of the top of the font is a circular opening surrounded by a collar 3. This collar is preferably provided with screw-threads for attachment of the wick tube. The wick tube 4 is preferably made of sheet metal. 40 The lower portion of the tube is formed of an enlargement 5, concentric to the tube. At the bottom, the walls of the tube are doubled back, forming a sleeve 6 of greater diameter than the enlargement 5. This 45 sleeve 6 preferably has screw-threads at its upper part for engagement of the threads upon the collar 3. The space between the enlargement 5 and the sleeve 6 constitutes an air jacket 7.

50 The wick tube may be removed from the font by rotating it so that the threads on the sleeve 6 become disengaged from the threads on the collar 3. The parts are best

proportioned so that when in position, the lower end of the tube is above the bottom 55 of the font a sufficient distance to allow the fluid to circulate below the same. The wick tube 4 contains a wick 8.

The vapor tube 9, valve 10, outlet tube 11 and burner ring 12 are the same as that 60 illustrated in my co-pending application previously identified. The burner ring is supported by means of a cage 13, which surrounds and is supported by the wick tube. Below the cage is a pan 14. The 65 pan is for the purpose of containing fuel which, upon being burned, will heat the upper part of the wick tube and thus generate vapor so that the lamp may be started.

Liquid fuel is introduced into the pan 14 70 by means of the pump 15. This pump comprises a barrel 16 closed at both ends. Within the barrel is the piston rod 17 having an operating handle 18. The lower end of the rod carries the piston 19, with 75 valve 20 thereon. At the bottom of the barrel is the bottom valve 21. Between the bottom of the barrel and the piston is a spring 22 for normally elevating the piston. The discharge orifice 23 is arranged at or adjacent to the top of the barrel and inside of 80 the pan 14. The orifice is also located on the side of the barrel toward the wick tube, so that when the fuel is discharged by the operation of the pump, it will be directed 85 toward the wick tube. Below the vapor tube 9 and secured thereto is a trough 14^a, which will catch any liquid fuel which may escape from outlet tube 11 and direct it to the priming pan. The lower end of the 90 trough 14^a is secured to the priming pan 14 by means of rivets 14^b. In operation, the handle 18 is depressed and elevated a few times, which operation raises the fluid in the barrel until it issues from the orifice 23 and 95 fills the pan 14.

The barrel of the pump, it will be noted, is supported at its lower end by the bottom of the sleeve and the upper end by the pan. The outside diameter of the barrel is pref- 100 erably the same as the width of the air jacket, so that the barrel makes a close fit between the enlargement 5 and the sleeve 6. This produces a rigid construction and holds the pump in position when the wick 105 tube is being screwed into or out of the font.

It is in such a location that the hand of the operator will naturally grasp the pump and unless it is rigidly held in position, it is liable to be disarranged.

- 5 According to my invention, the pump and tube being combined in one structure, avoids the necessity of making an additional opening in the top of the font; it avoids any pipe or other passage connecting the pump and 10 the priming pan, and withal produces a very compact, simple and satisfactory construction.

In accordance with the provisions of the 15 patent statutes, I have described the principle of my invention, together with the apparatus which I now consider to represent the best embodiment thereof; but I desire to have it understood that the apparatus shown is merely illustrative and that the invention 20 can be carried out in other ways.

Having now described my invention, what I claim as new and desire to secure by Letters Patent, is:—

- 25 1. A vapor lamp, which comprises a font, a wick tube with an outside sleeve separated therefrom by an air jacket, a pan carried by the tube, a priming pump carried by the tube, one end of the barrel of the pump being supported by the bottom of the sleeve

and the other end by the pan, the orifice of the pump discharging into the pan.

2. A vapor lamp, which comprises a font, a wick tube with an enlargement adjacent to the lower end, an outside sleeve separated from the enlargement and forming an air 35 jacket, a pan carried by the tube, a priming pump also carried by the tube, the orifice of the pump discharging into the pan, one end of the barrel of the pump being supported by the bottom of the sleeve, the other end of 40 the barrel being supported by the pan and an intermediate portion of the barrel being supported by the enlargement and the sleeve.

3. A vapor lamp, which comprises a font, 45 a wick tube communicating with the font, a vapor tube communicating with the wick tube, a priming pan carried by the wick tube, a pump carried by the wick tube and discharging into the priming pan, and a 50 trough extending between and secured to the vapor tube and priming pan.

This specification signed and witnessed this 18th day of June, 1913.

CHARLES NELSON.
